UNITED STATES PATENT OFFICE.

FRANK McINTYRE, OF NEW YORK, N. Y., ASSIGNOR TO EAGLE PENCIL COMPANY, OF NEW YORK, N. Y.

COMBINED CIGAR-LIGHTER AND PENCIL-POINT PROTECTOR.

1,074,555.

Specification of Letters Patent. Patented Sept. 30, 1913.

Application filed August 21, 1913. Serial No. 785,977.

To all whom it may concern:

Be it known that I, FRANK McINTYRE, a citizen of the United States, and a resident of the city of New York, in the county and State of New York, have invented a certain new and useful Combined Cigar-Lighter and Pencil-Point Protector, of which the following is a specification.

The cigar lighter which I have invented can be made and used as an article separate from a pencil. It, however, has been designed more particularly with reference to its use on a pencil point protector, and it is in this connection that I have illustrated it in the accompanying drawings. I shall first describe in connection with the said drawings, the article therein shown embodying my invention and will then point out more particularly in the claims those features of the same which I believe to be new and of my own invention.

In the drawings—Figure 1 is a view of the body and cap of the article, detached from one another. Fig. 2 is a side elevation of the complete device, with the cap (which carries the sparking member) fitted as a cover upon the tubular body (which contains the ignitable material). Fig. 3 is a longitudinal axial section of the device showing the cap, removed from over the tubular body, and fitted along side of the same in position to bring the sparking member upon it into operative relation with ignitable material in the tubular body.

A is the tubular body of the article, having one end fashioned as a point protector to receive the pencil P, and the other end utilized as a container for the ignitable material—which container, for convenience sake, will be termed the wick chamber. In the tube A, beyond the pencil point receiving portion thereof, is a tight fitting plug or partition a which divides the point receiving portion from the wick chamber and forms the bottom of said chamber. The ignitable material contained in the wick chamber may be of any suitable kind, preferably cotton b, or other absorbent material which will hold gasoline or other liquid fuel, and a wick c embedded in said absorbent substance.

The cap B, which fits as a removable cover on the wick chamber end of tube A, carries a sparking member of any known or suitable construction, consisting, in the pres-

ent instance, of a friction wheel F mounted in bearings on the top of the cap, and a stick of sparking material contained and movable in a suitable guideway in the cap, and spring pressed upwardly through a hole in the top of the cap toward and into contact with the periphery of the wheel. A sparking member of this general construction is old and not of my invention.

To use the device as a lighter, the cap must be lifted and removed from the body A to expose the wick, and must then be brought along side of the body in position to bring the sparking member on its top into operative relation with the wick, and there held while the friction wheel is actuated to produce the spark. In order to hold the cap accurately and firmly in this position, as well as to assure it in its other position when returned to and fitted on the wick chamber end of the body A, I make use of a stem h on the cap B and a tubular guide i for said stem on the body A. The stem h is a stiff stem, preferably of metal, secured at one end to one side of, and extending lengthwise of the cap, and of a length to project at its free end some distance beyond the mouth of the cap. The tubular guide i is upon one side of the body A and extends lengthwise of the same and is intended to receive and fit snugly upon the stem h, which can slide in it, the stem and guide being of similar shape or cross section. The stem and guide are of a shape in cross section—in this instance rectangular—which will permit the stem to slide lengthwise in the guide, but will prevent it from rotary movement therein.

In the position of parts shown in Fig. 2, the cap C is fitted as a cover upon the body A, with the stem h extending down into and through the guide i. To bring the parts to the position shown in Fig. 3, the cap C must first be lifted from over the body A far enough to completely draw the stem h out of and disengage it from the guide i; the cap is then given a half turn, so as to bring it along side of the body A, and it is then lowered in a path which will cause the stem h to enter and pass down through the guide i in which it will be held firmly against rotation. Means should be provided for arresting the downward movement of the cap along side the body, when the sparking member has been brought opposite to the wick, and for this purpose any suitable stop or arresting

device may be provided. I preferably employ for this purpose the opposed faces of the members h' i' by which the stem h and guide i are secured to the cap B and body A respectively, these members being so located that when the sparking member has reached its proper position opposite the wick, as in Fig. 3, the opposed faces of the members h' i' abut, and thus prevent further downward movement of the cap relatively to the body. In this position the sparking member is held with absolute security in its proper relation to the wick owing to the fact that the stem h is incapable of rotation in the guide i . To return the cap to the position shown in Fig. 2, the operation is reversed; but in either position, the cap must be lifted from and completely disengaged from the body A before it can be returned to the other position.

The friction wheel which preferably is made up of a number of serrated disks assembled and secured together upon an axle on which they can revolve, as indicated in Fig. 1, is provided with a lever handle projecting radially from its periphery and made integral with it. The teeth of the assembled disks need not match, and extend only part way around the periphery of the wheel. This lever handle normally occupies the upright position on the prolongation of the tube A and cap B shown in Fig. 2 of the drawings, where it is out of the way and in a position where it will not catch in the pocket or clothing.

What I claim herein as new and desire to secure by Letters Patent is:

1. The combination of the tubular body and wick chamber therein; the cap constituting a removable cover for said chamber;

the sparking member mounted on and carried by the cap; a stem attached at one end to the outside of the cap, extending lengthwise of said cap and beyond the mouth of the same; a tubular guide of similar cross section to the stem secured to the exterior of the body and extending lengthwise of the same, in position to receive and permit the passage through it of the stem, the stem having a shape in cross section to permit its lengthwise movement and prevent its rotation in the guide, and being free to be withdrawn and completely disengaged from the guide when desired, substantially as and for the purposes hereinbefore set forth. 55

2. The combination of the tubular body and wick chamber therein; the cap constituting a removable cover for the wick chamber; the sparking member carried by the cap; a stem attached at one end to the outside of the cap, extending lengthwise of said cap and beyond the mouth of the same; a tubular guide on the exterior of the tubular body, into which the stem may be inserted and moved lengthwise only, and from which it may be completely withdrawn so as to disengage the cap from the tubular body, and a stop to arrest the further sliding movement of the stem in the guide when the cap has been moved in a direction and far enough to bring the sparking member on it in operative relation to the wick chamber, substantially as and for the purposes hereinbefore set forth. 60 65 70

In testimony whereof I affix my signature in presence of two witnesses.

FRANK McINTYRE.
